(57) **CLAIM**

The ornamental design for a refrigerator, as shown and described.

DESCRIPTION

FIG. 1 is a front perspective view of a refrigerator showing our new design;

FIG. 2 is a top view thereof;

FIG. 3 is a front view thereof; and,

FIG. 4 is a right side view with the left side view being a mirror image thereof.

The unshown bottom surface and rear surface of the refrigerator forms no portion of the claimed design. Applicant recognizes that the inventive aspects of the current design exist in the refrigerator as a whole, in individual portions and elements thereof, and in combinations of portions and elements thereof. Applicant reserves the right to amend this application and/or to file one or more divisional or continuation applications to specifically claim any such configurations in line drawings.
